UNITED STATES PATENT OFFICE.

JAMES PORTEOUS, OF FRESNO, CALIFORNIA.

AEROPLANE.

1,302,214.

Specification of Letters Patent. Patented Apr. 29, 1919.

Application filed March 6, 1918. Serial No. 220,861.

To all whom it may concern:

Be it known that I, JAMES PORTEOUS, a citizen of the United States, and a resident of the city of Fresno, in the county of Fresno and State of California, have invented a new and useful Improvement in Aeroplanes, of which the following is a specification.

My invention relates to aeroplanes, and among the objects accomplished is to provide an inclosure in which the operators and passengers are not exposed to the wind and weather when flying, a plurality of engines and propellers arranged so that one or more can be stopped and removed while flying without interfering with the equilibrium of the machine, a combination in which some of the propellers can be reversed to slow the speed of the machine for ease in alighting, for placing the engines operating the propellers so that one or more of them can be stopped while flying without interrupting the general movement of the aeroplane; for arranging the planes and the carriage in such relation that the planes act on the principle of a parachute so that the suspended weight will keep the aeroplane from tipping over, and other objects which will be hereinafter referred to.

It should be observed that most of the objects sought to be accomplished are useful more especially in connection with an aeroplane of large powers intended to carry heavy tonnage and capable of traveling long distances, and not one capable of acrobatic performances.

In the drawing accompanying this specification Figure 1 shows a view of the aeroplane complete, as seen from the end carrying the propellers, with a part of the frame in section. Fig. 2 is a side view of the plane. Fig. 3 is an end view, partly in section, of the carriage attached to the plane, showing the relative locations of the propellers, and showing one propeller and the engine connected therewith removed to the interior of the carriage for adjustment, and also showing how the engines can be arranged in different locations in relation to the propellers. Fig. 4 is a side view of the carriage with parts cut away to show several modified arrangements of the engines and propellers which are possible, and showing that the operator has an unobstructed view through the glass front, which glass front is shown in section. Fig. 5 is a view of the

top of the frame of the machine showing extended webs to retard the speed in alighting. Fig. 6 is the same view as Fig. 5 without the webs. Fig. 7 is an end sectional view 60 of the inclosure, showing projecting supports for the engines and propellers with uniform engines, and propellers on the engine shafts, and showing one engine removed to the interior of the inclosure and resting 65 on a detachable slideway table for repairs. Fig. 8 is a top view of the frame support carrying the engine and propeller, and showing a detachable table top, and screw means for removing the engine and propeller into 70 the interior of the inclosure, and for replacing it in position for driving the aeroplane. Fig. 9 shows a portion of the interior wall of the inclosure, and ordinary means for closing the opening therein through which 75 the engine and propeller can be removed. Fig. 10 is an end view of the engine support showing the engine therein at the outside end of such support. Fig. 11 is a view of the engine and a sectional end view of the four 80 beams which form the slideways along section line *y* on Fig. 7. Fig. 12 is a detailed view of a journal attached to a supporting bracket carrying the screw used for removing the engine. Fig. 13 shows an end view 85 of the engine in relation to its position in the slideway on a table, and shows a sectional view of said slideway along sectional line *x* on Fig. 7.

In said drawings B represents the carriage in which is located the engine room, the pilot room and room for passengers or freight. Its front end *B*² is preferably of glass or transparent material so the view of the pilot is unobstructed. The inclosure can be extended the full length of the frame of the aeroplane. The shape of the inclosure is not material, and while Fig. 7 shows it octagonal, experience might show a parallelogram preferable, or show the engine room 95 round or octagonal and the remainder of the inclosure a parallelogram. Numbers 2, 21, 22, 23, 24, 25, and 26 are planes constructed in the usual manner on aeroplanes. The number of planes may vary, but there should be approximately one for each propeller. I have shown seven of such planes on the drawing, but a larger or smaller number can be used. There should be a plurality of them. The planes are arranged one above 100 the other on approximately horizontal lines, the object being to have the upper ones high 105 110

enough above the carriage so that the weight of the carriage and contents will be suspended from them on the same principle as a weight suspended from a parachute. This 5 construction is intended for the purpose of preventing the machine from tipping over, and for automatically adjusting its equilibrium to the movement of the passengers, operators, etc. Numbers 3 and 3^a, 31, 32, 33, 10 34, 35, 36 and 37 are a plurality of pairs of upright posts used to hold the planes a uniform distance apart. Each pair is a duplicate of the pair 3 and 3^a, shown in Fig. 2. The space between the end posts 3 and 3^a 15 and the pair designated as 37 can be filled in so that the space between the ends of the planes is inclosed. Numbers 4, 41, 42, 43, 44, 45, 46, 47 and 48 are a plurality of stay braces used in the ordinary manner of bracing 20 truss work to strengthen the framework carrying the planes. 5 is the main frame of the aeroplane extending the length of the machine at right angles to the planes. 58 is a portion of the main frame extending forward, and corresponding to the bowsprit of a ship. 51, 51^a, 52, 52^a, 53, 53^a, 54 and 54^a 25 are a plurality of guy wires extending from the forward end of the extensions 58 to the planes, their purpose being to make the framework of the aeroplane more rigid. While I have shown but eight of such wires on the drawings, I do not confine myself to that number, as a sufficient number should be used to support the planes against the 30 air pressure when flying. 56 and 57 are guy wires extending from the planes to the rear end of frame 5.

D, D¹, D², D³, D⁴, D⁵, D⁶ and D⁷ are a plurality of arms or propeller supports shown 35 on the drawing as extending radially from the carriage or inclosure B. These propeller supports can be inclosed as shown in Fig. 2, or can be frame work as shown in Fig. 7. The propellers do not necessarily have to be arranged in the order shown on the drawing. The primary object sought to be attained is the inclosure in which the operator and passengers can ride without being exposed to the air and weather, and as a base 40 for supports for carrying propellers outside the wall of the inclosure, and in such position that they are readily accessible from the inside of the inclosure. F, F¹, F², F³, F⁴, F⁵ and F⁶ are propellers shown in the drawing 45 as carried on the outside end of supports D. In the plan illustrated in each of the figures there should be one engine for each propeller, but this is not essential to the general plan, as one engine might be arranged to 50 drive two or more propellers, or more than one engine might be hitched to one propeller. I prefer a plurality of engines, each of which is operable without relation to the others except that an arrangement for 55 starting them all in unison through an elec-

trical arrangement or otherwise may be used, so that if an engine is disabled it can be stopped, and the only detrimental result will be the temporary discontinuance of a part of a plurality of power units. In Fig. 4 7^a I have shown two different arrangements for the engine. Engine E^{2a} (in Fig. 4) is shown in support D^a, outside of the main inclosure B, and having propeller F connected directly with the engine. Engine E^{4a} is shown 7^b within the main inclosure B, in which connection the propeller F⁴ is carried on a propeller support 6 extending outwardly from the wall of inclosure B, and power is conveyed to the propeller by means of belt 6^a. 8 In Fig. 3 I have shown three different forms of engines and different arrangements of the engines in relation to the inclosure B. E^{2b} and E^{4b} are one form of engine which is located wholly within the interior of the 8 main inclosure B. Engines E^{3b} and E^{5b} are located just outside the wall of inclosure B and are easily accessible from the interior of the inclosure. The propellers F², F³, F⁴ and F⁵ are supported on arms D D extending 9 outwardly from the inclosure, and said propellers are operated by means of sprocket chains f or other well known means for transmitting power. On the engines E^{3b} and E^{5b} I have shown ordinary means for reversing the propellers, such means consisting of a drive belt or sprocket, chain f, and a pair of gears g and j. The engines E¹, E², E⁷ and E⁸ are identical to those shown in Fig. 7.

N, shown in Fig. 5 is a web, preferably of canvas or linen, stretched from frame 5 to lower plane 26, for the purpose of reducing the shock of landing. O is the rudder for steering the machine, and Q is an elevator 1 for raising or lowering it when in flight. P are depending springs for the protection of the rudder and elevator when landing. L is a false floor in the interior of inclosure B, W are wheels to assist in starting a flight 1 or in landing.

The engine support D is preferably constructed of four strips of angle iron or metal, D^b, D^c, D^d, and D^e, which are arranged to form a slideway toward the approximate 1 center of the inclosure B. The outside frame of engine E is constructed to fit snugly within this slideway. E^a and E^b are ordinary bolts used to fasten the engine frame firmly to the engine support D when 1 the engine and propeller are in position for driving the aeroplane. M² are openings through the wall of inclosure B at the base of engine supports D, and are of sufficient size to permit the engine E and connected 1 propeller F to pass through. M is a plate, used as a door and is constructed to fit over opening M², which can be fastened to the wall of inclosure B in any suitable manner. H³ is a bracket fastened to the interior wall 1

of the inclosure B and adjacent to the opening M². H is a table one end of which can be attached to the bracket H³, and the other end of which is supported by a brace H². 5 This table has a recessed slideway H⁵ therein shown in section in Fig. 13, the slideway corresponding in width to the slideway in the engine support D. Table H can be adjusted to form a continuous slideway with 10 the slideway in engine support D. H⁴ is a journal at the inside end of table H. K is a screw which is operable through a threaded hole K², which hole is through a portion of the engine frame 5. K³ is a crank attached 15 to screw K. Adjoining the handle there should be a smooth portion having shoulders or collars, H^{4a} and H^{4b} at each end of the smooth portion, such smooth portion being fitted to journal H⁴. It will be noted 20 that by turning the screw K in one direction the engine E⁷ is forced along the slideways to a position at the outside end of the slideway in support D⁷, where the engine can be made to rotate the propeller F⁷. By reversing screw K, the engine and attached 25 propeller can be drawn through opening M² to the inside of the inclosure for repairs. Table H and the screw K can be moved to connect with the slideway of either of the 30 engine supports.

I claim as new and ask for Letters Patent upon:

1. In an aeroplane, the combination of a frame, a plurality of planes arranged along approximately horizontal lines a fixed distance apart, and connected to said frame, a closed carriage attached to said frame, a plurality of supports extending outwardly from the wall of said inclosure, slideways 35 within said support, and an engine having a propeller attached thereto, and fitted within a frame constructed to slide within said slideway, substantially as described and for the purposes set forth.
2. In an aeroplane having an inclosed carriage thereon, a plurality of openings through the wall of the carriage, a frame containing slideways extending outwardly from the wall of the carriage, and adjacent 40 to the openings in the wall of the carriage, and engines within frames fitted to slide within the slideways and propellers operated by said engines, substantially as described.
3. In an aeroplane having an inclosed carriage thereon, a plurality of frame supports 55 extending outwardly from, and attached to the wall of the carriage, a slideway extending lengthwise in each support, an auxiliary slideway of the same approximate width as the slideway in the support extending within 60 the interior of the carriage and forming a continuation of the slideway in the support, an engine in a frame adapted to slide within the slideway, an opening through the wall of the carriage in such relation to the slideways that the frame of the engine can be moved from the auxiliary slideway to the main slideway, substantially as described.
4. In an aeroplane having an inclosed carriage thereon, a plurality of frame supports 70 attached to the wall of the carriage and extending outwardly therefrom, a main slideway extending lengthwise in each support, an auxiliary slideway adapted to be attached to the inner wall of the carriage and to 75 form a continuation of the main slideway, an engine attached to a frame adapted to slide within the slideway, a propeller attached to the engine shaft, an opening through the wall of the carriage of such 80 size and location in relation to the slideways that the engine and attached propeller can be moved along said slideways, and screw means for moving said engine and frame within the slideways, substantially as described.
5. In an aeroplane having an inclosed carriage thereon, a plurality of supports extending outwardly from the carriage wall and attached thereto, a main slideway within 90 each of the supports, an adjustable extension of said slideway within the carriage inclosure, said adjustable extension being formed of channel iron, an engine within a frame fitted to slide within the main slideway, and 95 the channel iron slideway in the adjustable extension, a propeller attached to the shaft of each engine, and an opening through the wall of the carriage adjacent to each slideway of such size that the engine and the 100 propeller attached thereto can be drawn through such opening substantially as described and for the purposes set forth.

JAMES PORTEOUS.
